(57) **CLAIM**

The ornamental design for a tray for making and serving rolled foods, as shown and described.

DESCRIPTION

FIG. 1 is a top isometric view of the tray for making and serving rolled foods;

FIG. 2 is a bottom isometric view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a cross-sectional view thereof, taken along line 7-7 in FIG. 3;

FIG. 8 is a front elevational view thereof; and,

FIG. 9 is a rear elevational view thereof.

The diagonal shade lines in the drawings denote that the surfaces of the tray for making and serving rolled foods are reflective.

1 Claim, 6 Drawing Sheets
